[57] **CLAIM**

The ornamental design for a dart game target, as shown and described.

DESCRIPTION

FIG. 1 is a front view of the dart game target, showing my new design, the broken line showing of the numerals is for illustrative purposes only, and forms no part of the claimed design; and,

FIG. 2 is a side view of the dart game target.

The top, opposite side and bottom views of the dart game target are identical with FIG. 2.

The appearance of the back of the dart game target forms no part of the design invention.
